UNITED STATES PATENT OFFICE.

DENNIS LEONARD, OF CLEVELAND, OHIO.

DESIGN FOR A HANDLE-LUG.

SPECIFICATION forming part of Design No. 32,071, dated January 2, 1900.

Application filed December 8, 1899. Serial No. 739,715. Term of patent 7 years.

To all whom it may concern:

Be it known that I, DENNIS LEONARD, a citizen of the United States of America, and a resident of Cleveland, county of Cuyahoga, and State of Ohio, have invented and produced a new and original Design for Handle-Lugs for Coffins or Burial-Caskets, of which the following is a specification, reference being had to the accompanying drawings, forming a part thereof.

In the drawings, Figure I is a front side elevation of a handle-lug embodying my design. Figs. II and III are opposite end elevations, respectively, of the lug. Fig. IV is a top plan of the same.

The central portion 5 of the lug bulges forwardly and is rounded. A continuous shoulder 6 extends around the upper portion and end portions of the said forward and bulging central member of the lug, and a continuous surface 7 forms the end portions and upper portion of the lug, and consequently is arranged rearwardly of and extends along the aforesaid shoulder from end to end of the latter and forms the end portions and upper portion of the lug. The aforesaid shoulder is ornamental. Ornamental figures 8 are formed at intervals along the edge of the lug. 25

The essential or characteristic features of this design are the centrally-located forwardly-bulging portion of the lug, the shoulder extending around the top and ends of the said forwardly-bulging portion of the lug, and the continuous surface arranged rearwardly of and extending along the said shoulder. 30 35

What I claim is—

The design for a handle-lug, substantially as shown and described.

Signed by me at Cleveland, Ohio, this 27th 40 day of November, 1899.

DENNIS LEONARD.
